UNITED STATES PATENT OFFICE.

FRANK A. BEAN, OF CARROLLTON, OHIO.

TROLLEY-WIRE HANGER.

1,220,062.

Specification of Letters Patent. Patented Mar. 20, 1917.

Application filed July 13, 1915. Serial No. 39,685.

To all whom it may concern:

Be it known that I, FRANK A. BEAN, a citizen of the United States, residing at Carrollton, in the county of Carroll and State 5 of Ohio, have invented certain new and useful Improvements in Trolley-Wire Hang-
ers, of which the following is a specifica-
tion.

My invention relates to trolley wire sup-
ports, and more particularly to an im-
proved clamping ear for use in connection
with a trolley wire or like conductor.

The primary object of my invention is to
provide a trolley wire support which may be
easily and quickly attached to and detached
from the cross arm of a supporting pole,
and which will securely and positively re-
tain a trolley wire or the like conductor in
position.

Another object of my invention is to pro-
vide a trolley wire support which may be
adapted for use either in connection with
supports of the cross arm type or in connec-
tion with span wire supports.

With the above and other objects in view
my invention resides preferably in the con-
struction, combination, and arrangement of
parts as hereinafter set forth in the specifica-
tion and illustrated in the accompanying
drawings, in which—

Figure 1 is a side elevation of a trolley
wire support embodying the improvements
of my invention.

Fig. 2 is an end elevation of the same.

Fig. 3 is a vertical sectional view taken on
the line 3—3 of Fig. 1.

Fig. 4 is an elevational view of a modi-
fied form of my invention.

Similar reference characters indicate simi-
lar parts throughout the various views of
the drawings.

In the drawings, wherein the preferred
embodiment of my invention is illustrated, a
cross arm 1 of the usual trolley supporting
pole is shown. My invention includes a
body 2 substantially frusto-conical in shape
and having a frusto-conical central bore 3
therein.

A supporting frame for the body 2 is
provided including a plurality of arms 4
and 5 having semi-circular portions 6 and
7, respectively, and formed with clamping
portions 8 and 9, respectively. Suitable
clamping bolts 10 extend through the arms

4 and 5 in order to securely maintain the 55
same in engagement with the cross arm 1.

The trolley wire engaging ear comprises
a pair of clamping members 11 and 12 hav-
ing their lower adjacent extremities formed
to provide clamping jaws 13 and 14, respec- 60
tively, said clamping jaws engaging a
grooved trolley wire 15. The clamping
member 11 is provided on its upper extremity
with a threaded shank 16 on which a re-
taining nut 17 is receivable. The inner face 65
of the clamping member 11 is provided with
a recess 18 and an inclined face 19. The
clamping member 12 is provided with a
projecting portion forming a shoulder 20
for engagement in the recess 18, said clamp- 70
ing members having their adjacent faces
complementally inclined as shown to ad-
vantage in Fig. 3. The clamping members
when assembled are substantially frusto-
conical adjacent their upper extremities for 75
reception in the bore 3 of the body 2, said
bore being lined with suitable insulating
bushing 21, an insulating washer 22 being
interposed between the nut 17 and the up-
per end of the body 2. It will be seen that 80
in clamping a wire or the like conductor, the
sections of the clamping element are assem-
bled and the clamping jaws are engaged
with the grooves of the conductor. The
clamping members 11 and 12 are now in- 85
serted in the bore 3 and the nut 17 disposed
thereon. Upon tightening the nut the sec-
tions 11 and 12, by virtue of their inclined
faces, being of frusto-conical contour when
assembled will be wedged into the bore 3 of 90
the body 2 securely clamping a wire or the
like conductor.

In Fig. 4 a modified form of the invention
is shown, the body 2 having the arms 6 and
7 eliminated and replaced with lugs 23, said 95
lugs having openings 24 therein to receive
the extremities of suitable span wires. The
other parts of this form of the invention are
substantially identical with that form of the
invention hereinbefore shown and described. 100

It is thought from the above description
taken in connection with the accompanying
drawing that a clear and comprehensive un-
derstanding of the construction, use, and
advantages of my invention may be readily 105
gathered. It will be noted that the range
of uses to which the invention may be placed
is unlimited, the principal novelty lying in

the peculiar manner in which the clamping elements of the invention are constructed. It will also be noted that soldering or welding of the trolley ear which is common at the present time is obviated when my invention is used, which not alone is cheaper in construction but also saves considerable time when erecting an overhead conductor. It is to be understood, of course, that while I have shown and described my invention as embodying a peculiar form and construction, certain changes may be made in the details thereof which do not depart from the spirit and scope of the invention as claimed.

15 What is claimed is:

1. In a trolley wire hanger, a supporting body having an opening therein, a clamping element including a pair of wire engaging arms, one of said arms having a pocket formed therein and a screw threaded shank upon its upper end, a hooked portion formed upon the remaining arm received by said pocket, said arms adapted for reception in the opening in the supporting body, and

means engaged with said screw threaded shank for maintaining the arms upon the supporting body.

2. In a trolley wire hanger, a supporting body having a frusto-conical opening therein, a clamping element including a pair of arms having wire engaging jaws formed upon the lower extremities thereof, one of said arms being provided with a pocket and a screw threaded shank arranged upon its upper end, a hooked portion formed upon the remaining arm received by said pocket, said arms being of a shape complementary to the shape of the opening in the body and receivable thereby, and means engaged with said screw threaded shank for maintaining the arms upon the supporting body.

In testimony whereof I affix my signature in presence of two witnesses.

FRANK A. BEAN.
